(57) **CLAIM**

The ornamental design for an electronic cigarette charging base as shown and described.

DESCRIPTION

1.1 : Perspective

1.2 : Perspective

1.3 : Front

1.4 : Back

1.5 : Left

1.6 : Right

1.7 : Top

1.8 : Bottom

The present design relates to an electronic cigarette charging base; reproduction **1.1** is a top perspective view of the electronic cigarette charging base of the present design; reproduction **1.2** is a bottom perspective view thereof; reproduction **1.3** is a front view thereof; reproduction **1.4** is a rear view thereof; reproduction **1.5** is a left side view thereof; reproduction **1.6** is a right side view thereof; reproduction **1.7** is a top view thereof; and reproduction **1.8** is a bottom view thereof.

(Continued)

The broken lines in the drawings depict portions of the electronic cigarette charging base that form no part of the claimed design.
